UNITED STATES PATENT OFFICE.

CHARLES C. SPENGLER, OF ROCKFORD, ILLINOIS, ASSIGNOR TO AUTOMATIC PENCIL SHARPENER COMPANY, OF CHICAGO, ILLINOIS, A CORPORATION OF NEW YORK.

PENCIL-HOLDING MEANS FOR PENCIL-SHARPENERS.

1,118,693.

Specification of Letters Patent. Patented Nov. 24, 1914.

Application filed January 24, 1912. Serial No. 673,094.

To all whom it may concern:

Be it known that I, CHARLES C. SPENGLER, a citizen of the United States, residing at Rockford, in the county of Winnebago and 5 State of Illinois, have invented certain new and useful Improvements in Pencil-Holding Means for Pencil-Sharpener, of which the following is a specification.

This invention relates to chucks to be used 10 on pencil sharpeners for the purpose of holding and rotating the pencils that are being sharpened. In some of the pencil holders or chucks heretofore produced, the jaws are pressed inwardly to grasp the 15 pencil by means of either leaf or coiled springs. These prior chucks, however, have been found unsatisfactory in practice for the reason that they grip different sizes of pencils to be sharpened with different degrees of force. To operate satisfactorily 20 the chuck must grip the pencil with sufficient force to insure rotation of the latter therewith, but not tightly enough to prevent the pencil from being drawn or fed downwardly to the cutting means. In previous 25 chucks, if the relation of parts was such that a small-sized pencil would be gripped firmly enough to insure rotation of the pencil, then a large-sized pencil would be 30 held so tightly that proper downward feeding movement thereof could not be had. On the other hand, if the chuck gripped a large-sized pencil lightly enough to permit free downward feeding movement thereof, a 35 small-sized pencil would not be engaged with sufficient force to cause rotation thereof with the chuck.

It is the object of my invention to produce a chuck which will grip all sizes of 40 pencils with substantial uniformity. As ancillary to the main object of the invention it is my purpose to provide a chuck of simple and durable construction and one which is inexpensive to manufacture.

45 In the accompanying drawings, Figure 1 is a front elevation of a pencil sharpener equipped with a pencil chuck embodying my invention. Fig. 2 is a fragmental vertical section on line 2 of Fig. 1. Fig. 3 is a vertical section of the chuck with a large pencil

inserted. Fig. 4 is a vertical section of the chuck with a small pencil inserted. Fig. 5 is a cross-section of the chuck and pencil on the line 5 5 of Fig. 3. Fig. 6 is a fragmental plan view of the chuck with the pencil inserted and a portion of the casing broken away to show details of the chuck.

The pencil sharpener to which my improvements are herein shown as applied is of the type illustrated in the Gilfillan Patent No. 832,054, issued October 2, 1906. But it is to be understood that the chuck is not limited in its use to any particular form of pencil sharpener. The sharpener comprises a base 1 in which is slidably mounted the 60 drawer 2, the upper wall of said base having an opening 3 therein through which the shavings and dust from the pencils fall into the drawer 2. Surrounding the opening 3 are guard walls 4. Mounted upon the top 65 wall of the base 1 is a disk 5 having a plane face 5^a on one side and having a boss 6 formed upon its opposite side. Through this boss extends an opening or bore 7 adapted to receive the end of the pencil which is 70 to be sharpened. The opening 7 extends at an angle to the plane face 5^a of the disk 5 and terminates at its lower end upon said face.

The cutting means may be of any suitable 80 form, that herein shown comprising a plurality of rotating blades 8 lying against the face 5^a of the disk 5, said blades arranged to be rotated by means of a suitable crank handle 9 to move successively over the open 85 lower end of the bore 7 so as to cut off the portion of the pencil protruding through said lower end. As each knife cuts off a portion of the pencil it draws the pencil bodily downward a slight distance.

90 The means for frictionally engaging the pencil A to rotate the latter, which I designate as the chuck, is rotatably mounted upon the upper end of the boss 6, said means comprising, in the present embodiment, a sleeve 95 10 having an extension 11 at its lower end, which, in this instance, is seated in a countersink in the upper end of the opening or bore 7. Fixed upon the extension 11 is a toothed wheel 12 adapted to be engaged by 100

any suitable means for intermittently rotating the pencil holder or chuck. A member 13 having spring arms 14 lies at opposite sides of the sleeve 10 and engages the upper 5 side of the toothed wheel 12 for the purpose of holding the extension 11 seated in the countersink, and also to frictionally hold the sleeve against rotation through momentum.

10 The sleeve 11 has a plurality of openings 15 in its sides, above which and suitably attached to said sleeve, is an annular flange 16. A housing or cap 17 is secured to the flange 16 in any suitable way as by means of 15 screws 18 threaded into said flange. Said housing incloses the upper portion of the sleeve 10 and the gripping means to be now described.

15 The gripping means comprises a plurality 20 (in this instance four) of fingers or jaws 19, which, in the exemplary embodiment herein disclosed, take substantially the form of the letter U. The upper or free end of one of the arms 20 of each jaw is pivotally attached 25 to the chuck in any suitable manner, that herein shown comprising a plurality of notches 21 in the periphery of the flange 16 and above the openings 15, the free ends of the arms 20 of the jaws lying in these 30 notches and each having lugs 22 overlying the edges of the notches and engaging the upper surface of the flange 16. Bosses 23 formed in the housing 17 provide chambers 24 in which the upper ends of the arms 20 lie, said chambers serving to hold said upper 35 ends in proper position, but permitting the necessary movement thereof. The other arm 25 of each of the jaws 19 is reduced at its free end, as at 26, to provide shoulders 27. 40 Surrounding the reduced ends 26 of the arms 25 and bearing at one end against the shoulders 27 are coiled springs 28, the other ends of which bear against the housing 17. The fingers 19 and springs 28 normally extend 45 diagonally with respect to the sleeve 11.

By a comparison of Figs. 3 and 4, the former figure showing a large pencil and the latter figure a small pencil inserted into the chuck, it will be noticed that when the jaws 50 19 are forced to their outermost position by a large pencil, the direction of force exerted by the springs 28 is more nearly parallel to the jaw than when a small pencil is inserted, as shown in Fig. 4. As the jaws are 55 forced outwardly from their innermost position the direction of pressure of the springs 28 gradually shifts, from a line more or less transverse to the extent of the jaws, toward a line parallel to the jaws. By reason of 60 this operation of the springs and jaws the effective gripping action of the jaws upon the pencil is maintained substantially constant for all sizes of pencils. This is due to the fact that the force of the springs actu-

ally transmitted to the jaws when in their outer position is less than when in their innermost position, because in the former position the springs act more nearly in a line with the jaws, and thus exert part of their force in pulling downwardly on the pivots 70 of the jaws, while in the latter position the springs act in a direction at a greater angle with respect to the jaws. And this direction of pressure of the springs gradually shifts as the jaws are moved one way or the other, with the result that the effective gripping pressure of the jaws is maintained constant for all sizes of pencils.

75 In the operation of the sharpener, a pencil is inserted in the chuck and pressed downward into the opening 7. The knives are rotated by means of the handle 9 and the knives cut the wood from the pencil, and, at the same time, gradually draw the pencil downward until it rests upon the stop 29. 80 Between each cut of the knives the toothed wheel 12 is engaged to move the pencil chuck 85 through a partial rotation.

It should be understood that the invention 90 is not limited to the details of construction herein shown and described, but may be modified in various ways without departing from the spirit and scope of the invention.

I claim as my invention:

1. A chuck for pencil sharpeners having 95 pivoted gripping jaws, and coiled springs acting on said jaws and tending to swing them inwardly, said springs extending longitudinally alongside of the jaws.

2. A pencil chuck comprising a sleeve 100 adapted to receive a pencil and having openings in its sides, a housing attached to said sleeve, U-shaped pencil-gripping jaws extending through said openings in position to grip a pencil, each of said jaws being pivoted by the free end of one of its arms, and coiled springs each bearing at one end 105 against said housing and at its other end upon the other arm of one of said U-shaped jaws.

3. A pencil chuck comprising a sleeve adapted to receive a pencil, and having openings in its sides, a flange fixed to the upper end of said sleeve, a housing secured to said sleeve, a plurality of pencil-gripping jaws extending through said openings in position to grip a pencil, each of said jaws being of approximate U-shape 115 and having the free end of one of its arms pivotally supported by said flange, and coiled springs each bearing at one end against said housing and at its other end against the other arm of one of said U-shaped jaws.

4. A pencil chuck comprising a body 125 adapted to receive a pencil, pivoted fingers adapted to grip the pencil, said fingers being positioned diagonally with respect to

the pencil, and coiled springs acting upon said fingers, and also being positioned diagonally.

5. A pencil chuck comprising a sleeve having openings in its walls, a housing mounted on said sleeve, a plurality of fingers pivoted at their ends and extending diagonally through said openings into position to grip a pencil, and coiled springs positioned diagonally with respect to said sleeve,

each of said springs bearing at one end against one of said fingers, and at its other end against said housing.

In testimony whereof I affix my signature in the presence of two witnesses.

CHARLES C. SPENGLER.
